(57) **CLAIM**

The ornamental design for a fan forced heater, as shown and described.

DESCRIPTION

FIG. 1 is a front and side perspective view of fan forced heater showing my new design;

FIG. 2 is a front elevational view thereof;

FIG. 3 is a side elevational view thereof from the left of FIG. 2, the side opposite that shown in FIG. 3 being the mirror image thereof;

FIG. 4 is a rear elevational view thereof;

FIG. 5 is a top plan view thereof; and,

FIG. 6 is a bottom plan view thereof.
